UNITED STATES PATENT OFFICE.

JOHN J. WILT, OF BAKERSFIELD, CALIFORNIA.

VAPOR CONDENSER.

Application filed March 22, 1926. Serial No. 96,493.

My invention relates to and consists in a novel means for receiving vapor escaping from liquid-containers, condensing said vapor and returning the condensate to the container, to the end that evaporation losses from and accumulation of pressure in said container may be prevented.

My invention is applicable to any appliance or equipment in the use of which the objects sought may be of advantage; and, it is to be understood that in the illustration herein made, details of structure and form in the device may be changed without departing from the spirit of the invention as defined by the claims hereunto appended.

In the accompanying drawings, to which reference is made—

Fig. 1 is an elevation, partly in section, of my vapor condenser as applied to a removable closure plug in original manufacture and assemblage.

Fig. 2 is an elevation of the stand-member of the device as adapted for application to a plug not already equipped, or to any closure-member or cover, where a plug is not used.

Referring to Fig. 1, the numeral 1 is the stand-member of the device. It is a rigid stem, having a foot which, in the instance here shown is one form of removable closure plug comprising the body 2, with its fitting or retaining lugs 3, top flange 4 and gasket 5.

In this foot plug are the usual passages 6 leading to the vertical vent 7 which extends up into the stand-member proper, above the foot-plug for a short distance, and thence opens out through the side of the stand-member as shown at 8.

The upper end of the stand-member 1 is best formed with a relatively extensive plano-convex head 9.

10 is an inflatable member. It is best formed as a light, rubber bulb, having a gripping neck 11. The bulb is fitted over the stand-member 1, resting on the head 9 on said member, while its neck 11 resiliently embraces the stand-member in a zone below the side vent 8 of said stand-member.

50 In order to make the grip of the neck 11 yieldingly effective, the stand-member is best formed with a bend at 12.

In operation, the vapor escaping from a liquid container, not shown, passes through the vent 6 of its plug or other closure member and out through the vent 8 of the stand-member into the inflatable member 10. This member expanding, compensates for pressure increase, up to a limit of excess pressure, which latter is automatically relieved by the yielding of the resilient neck grip 11 of the bulb 10. Up to this possible limit, however, relief of pressure in the liquid container is afforded, and the vapor is condensed in increasing volume as the bulb 65 expands, the condensate draining back through the vents into the liquid container, so that evaporation loss is prevented.

Referring to Fig. 2, the stand-member 1 is similar in all respects to the stand-member of Fig. 1, except that its foot is provided with threads 13, whereby it is adapted for plugs already made, or for other closure-members where no plugs are used.

I claim:—

1. In combination with a vented closure-member of a liquid-container, an inflatable-member in receiving and draining communication with the vent of said closure-member, and resiliently associated with said closure-member to afford automatic release of excess pressure.

2. A vapor-condenser comprising a stand-member associated with a vented closure-member of a liquid-container, said stand-member having a vent in receiving and draining communication with the vent of said closure-member; and an inflatable member fitted to said stand-member over the vent thereof.

3. A vapor-condenser comprising a stand-member associated with a vented closure-member of a liquid-container, said stand-member having a vent in receiving and draining communication with the vent of said closure member; and an inflatable-member in communication with the vent of said stand-member, said inflatable member being resiliently fitted to said stand-member to afford automatic release of excess pressure.

In testimony whereof I have signed my name to this specification.

JOHN J. WILT.
